UNITED STATES PATENT OFFICE.

LUCIUS E. COLEMAN AND WILLIAM H. SPAKE, OF ANAHEIM, CALIFORNIA;
SAID COLEMAN ASSIGNOR TO SAID SPAKE.

TOY ANIMAL.

No. 846,009.

Specification of Letters Patent.

Patented March 5, 1907.

Application filed October 9, 1906. Serial No. 338,178.

To all whom it may concern:

Be it known that we, LUCIUS E. COLEMAN and WILLIAM H. SPAKE, citizens of the United States, residing at Anaheim, in the county of Orange and State of California, have invented a new and useful Toy Animal, of which the following is a specification.

This invention has relation to toys; and it consists in the novel construction and arrangement of its parts, as hereinafter shown and described.

The object of the invention is to provide a toy which is adapted to be trundled on the surface of the ground and which is provided with a wheel eccentrically mounted so that the rear portion of the toy will have an accelerated vertical reciprocatory movement, while the forward portion of the toy will have but slight vertical movement. The body of the toy preferably represents a rabbit, the movements of which while running are substantially the same as those above indicated—that is to say, the whole body of the animal does not rise and fall simultaneously, as that of a horse or dog while running, but the vertical movement of the rear portion of the animal is greatly in excess of the vertical movement of the forward portion thereof.

In the accompanying drawing the figure is a side elevation of the toy with parts broken away and parts in section.

The representation of the body of the animal 1 is provided with a curved or rocker base 2. The shaft 3 passes transversely through the forward portion of the figure, and the wheel 4 is concentrically mounted upon the said shaft 3 and projects a slight distance below the curved edge 2. The shaft 5 passes transversely through the rear portion of the figure of the animal, and the wheel is eccentrically mounted upon the said shaft 5. Said wheel 6 also projects below the curved edge 2 of the figure. The wheels 4 and 6 are preferably concealed from view

within the figure 1. The push-rod 7 is provided at its lower end with the bifurcations 8, which embrace the figure 1 and which are attached to the shaft 3.

From the foregoing description it is obvious that as the figure is trundled over the ground the rear end of the figure by reason of the eccentric wheels 6 will be given an accelerated vertical reciprocatory movement, while the forward end of the figure by reason of the concentric wheel 4 will be devoid of such movement to a perceptible degree. Thus the movements of a rabbit while running will be closely imitated.

Having described the invention, what we claim as new, and desire to secure by Letters Patent, is—

1. A toy comprising a figure, a concentrically-journaled wheel supporting the forward portion of the figure, an eccentrically-journaled wheel supporting the rear portion of the figure and means for trundling the figure.

2. A toy comprising a figure having a longitudinally-curved base, a wheel concentrically journaled and supporting the forward portion of the figure, a wheel eccentrically journaled and supporting the rear portion of the figure and means for trundling the figure.

3. A toy comprising a figure, a concentrically-journaled wheel supporting the forward end of the figure, an eccentrically-journaled wheel supporting the rear portion of the figure and a push-rod pivotally attached to the figure in alignment with the center of the concentrically-journaled wheel.

In testimony that we claim the foregoing as our own we have hereto affixed our signatures in the presence of two witnesses.

LUCIUS E. COLEMAN.
WILLIAM H. SPAKE.
